JACOB H. WEISBROD, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

FLOOR AND WALL CONNECTION FOR RAILWAY-CARS.

1,183,934.

Specification of Letters Patent. Patented May 23, 1916.

Application filed May 28, 1915. Serial No. 30,943.

To all whom it may concern:

Be it known that I, JACOB H. WEISBROD, a citizen of the United States, residing at St. Louis, Missouri, have invented a certain new and useful Improvement in Floor and Wall Connection for Railway-Cars, of which the following is a full, clear, and exact description, such as will enable others skilled in the art to which it appertains to make and use the same, reference being had to the accompanying drawings, forming part of this specification.

My invention relates generally to railway cars and particularly such cars as are utilized for carrying grain, the principal object of my invention being to provide a comparatively simple and effective joint or connection between the side wall and floor of the car and which joint or connection, in addition to being weather-proof, will be effective in preventing the leakage of grain, even though the flooring and side wall sheathing tend to shrink away from each other as a result of drying out.

It will be understood that in the construction of cars for carrying grain, the flooring and the sheathing forming the side wall are constructed of comparatively thick lumber and when the same dries out there is a tendency for said flooring and sheathing to shrink, thereby opening the joint between said parts, which action results in a loss of grain forming the lading of the car and which loss is chargeable to the railway or transportation company owning the car.

I propose to provide a comparatively simple and inexpensive structure which will connect and maintain in proper relative positions the flooring and wall sheathing of a car and which structure will prevent the leakage of grain, even though the wood forming the flooring and sheathing shrinks to an abnormal degree.

A further object of my invention is to provide a grain-tight joint at the intersection of the floor and side wall which will readily permit the removal of the floorboards without disturbing the wall sheathing.

With the foregoing and other objects in view, my invention consists in certain novel features of construction and arrangement of parts, hereinafter more fully described,

claimed and illustrated in the accompanying drawings, in which—

Figure 1 is a vertical section taken through the side of a car adapted for carrying grain and which car is equipped with a joint of my improved construction between the flooring and wall sheathing. Fig. 2 is an enlarged detail sectional view of the joint between the flooring and wall sheathing. Fig. 3 is a sectional view similar to Fig. 2 of a modified form of the joint. Fig. 4 is a sectional view similar to Fig. 2 and illustrating a further modification of the joint. Fig. 5 is a sectional view similar to Fig. 2 and illustrating a further modification of the joint.

Referring by numerals to the accompanying drawings and particularly to the construction illustrated in Figs. 1 and 2, 10 designates the side sill member of the car underframe, 11 the car flooring, 12 the sheathing forming the wall of the car, which sheathing is of the usual matched tongue and groove type, and 13 the vertical members or posts which are fixed to and extended upwardly from the side sill 10 and to which members the sheathing 12 is fixed. 80 These upright members are usually in the form of Z-bars.

The lower member of the wall sheathing rests directly on top of the sill member 10 and the lower inner corner of said lower member is rabbeted as designated by 14 in order to receive the vertical leg *a* of a joint member 15, the same being preferably in the form of an angle with the inner portion of its horizontal leg *b* resting directly on top 90 of the inner portion of sill 10.

The lower member of the wall sheathing is rigidly fixed to the vertical flange *a* of joint member 15 in any suitable manner, preferably by means of bolts such as 16, the outer portions of which pass through the inner flanges of the upright members 13, and the outer threaded ends of said bolts being provided with nuts.

The end portions of the timbers forming the flooring 11 rest directly upon the horizontal leg *b* of angle 15 with the upper outer edges of said flooring timbers bearing directly against the inner face of the lower wall sheathing immediately above the rabbet 14.

The edge of the flooring is rigidly fixed to joint member 15, preferably by means of wood rivets such as 17, the same passing vertically through the flooring members and 5 through that portion of leg *b* of the joint member which projects inwardly from the sill 10. Thus it will be seen that the flooring and sheathing are connected through the medium of joint member 15 and that the 10 latter rests directly upon the sill 10 and is fixedly held in proper position by the bolts 16 or like fastening devices which are seated in the upright or diagonal members forming a part of the side structure of the car. 15 By virtue of such construction the tendency of the flooring and wall sheathing to pull away from each other as a result of shrinkage is reduced to a minimum and in the event that the joint between these parts 20 does open to a limited extent said open joint will be rendered weather-proof and the leakage of grain will be prevented by the angle joint member 15 which serves as a connection between the sheathing and flooring. 25 In the modification illustrated in Fig. 3, the rabbet 14 is extended upward above the surface of the flooring, thus forming an opening into the space between the vertical leg *a* of angle 15 and the end of the flooring, and such construction permits a suitable filling such as cement to be placed in 30 said space.

In the construction illustrated in Fig. 4 a plate 18, preferably of metal, is rigidly 35 fixed in any suitable manner to the top of sill 10, a portion of said plate projecting inwardly from said sill. Loosely arranged on top of the outer portion of this plate is a tenon plate 19 having a continuous upwardly projecting rib 20, the same occupying a position in the groove 21 which is formed in the lower end of the members of 40 the wall sheathing. The outer edge of tenon plate 19 is bent downwardly as designated by 22 over the outer edge of plate 18, thus 45 maintaining the continuity of the outer surfaces of the wall sheathing and sill 10. The outer portion of the flooring 11^a rests directly upon the inner portion of plate 18 50 and these parts are fixed to each other in any suitable manner, preferably by means of wood-rivets 23 and the outer edge of said flooring bears directly against the lower inner portion of the wall sheathing. By virtue 55 of this construction, the flooring is prevented from drawing away from the side sill and the wall sheathing, and in the event that the latter should draw away from the sill through shrinkage or for any other reason, 60 the tenon plate positioned beneath said wall sheathing will at all times maintain a weather and grain proof joint.

In the modification illustrated in Fig. 5, the vertical leg of the angle member 15^a is 65 not connected to the lower sheathing mem-

ber 12 and the rabbet in said lower sheathing member is comparatively shallow or only of sufficient depth to receive the vertical leg of the angle.

A particular advantage gained by my improved construction arises from the fact that in all instances the ends of the floorboards do not extend beyond the inner face or surface of the wall sheathing and for this reason the flooring can be readily removed 75 without disturbing said sheathing.

Heretofore in the construction of grain-tight joints at the inter-section of the car floor and side walls, the practice has been to interlock the floor-boards with the sheathing 80 by either rabbeting the floor and sheathing boards or by rabbeting the sheathing boards only. In such construction the floor-boards cannot be removed without first removing a section of the side wall. It will be noted 85 that in my improved construction the ends of the floor-boards terminate in the same vertical plane with the inner face of the wall sheathing and by virtue of such construction, the flooring can be easily and 90 quickly removed without disturbing the walls.

To avoid cutting of the floor-boards at their ends, the vertical flange of the joint member is spaced apart from the ends of the 95 floor-boards a sufficient distance to receive the heads of the bolts which secure the joint member to the side framing members and sheathing of the car.

The joint member may be bolted only to 100 the floor-boards as illustrated in Fig. 5, and where such construction is employed, the floor-boards are retained upon the side sill and upward movement of said floor-boards is prevented by the vertical flange of the 105 joint member 15^a which occupies the recess in the wall sheathing.

A joint or connection of my improved construction is comparatively simple, requires no special shapes, is applicable for 110 either new cars or cars which are re-built or repaired, maintains the flooring and sheathing in proper relative positions, and prevents the opening of joints between said parts.

It will be readily understood that minor changes in the size, form and construction of the various parts of my improved joint or connection can be made and substituted for those herein shown and described, without 120 departing from the spirit of my invention, the scope of which is set forth in the appended claims.

I claim:

1. In car construction, a side sill, flooring, 125 wall sheathing, a joint member resting loosely upon said side sill and interposed between said flooring and sheathing and attaching means seated in a portion of said joint member and said wall sheathing.

2. In car construction, a sill, flooring, wall sheathing, a joint member resting loosely upon said sill and interposed between the flooring and sheathing, and means seated in 5 said joint member and the floor and sheathing for securing said parts to each other.
3. In car construction, a sill, side posts, flooring, wall sheathing, and a joint member resting upon said sill between the flooring 10 and sheathing, and which joint member is rigidly fixed to said flooring, sheathing, and side post.
4. In car construction, a side sill, side posts, flooring, wall sheathing, a joint member 15 resting upon said sill and interposed between the flooring and sheathing, means for rigidly fixing the joint member to the flooring, and means for rigidly fixing the joint member to the sheathing and side posts.
5. In car construction, a side sill, a joint member bearing loosely thereupon, flooring secured to said joint member, wall sheathing and attaching means seated in said joint member and wall sheathing.
6. In car construction, a side sill, a joint member bearing loosely thereupon, flooring secured directly to said joint member, side 20 posts, and wall sheathing arranged adjacent to said side posts, which sheathing, side posts, and joint member are secured to each other.
7. In car construction, a sill, flooring, wall sheathing, a joint member bearing loosely upon the sill and interposed between and 25 rigidly fixed directly to said flooring and sheathing, and said sheathing being rabbeted to receive a part of said joint member.
8. In car construction, a sill, flooring, wall sheathing, an angle supported by and bearing 30 loosely upon the sill and the legs of which angle are rigidly fixed to the flooring and sheathing.
9. In car construction, a side sill, flooring, wall sheathing, an angle loosely arranged 35 and bearing directly upon the sill with one of its legs positioned between the flooring and sheathing, and said angle being rigidly fixed directly to the flooring and sheathing.
10. In car construction, flooring, wall 40 sheathing, a joint member interposed between and rigidly fixed directly to said flooring and sheathing and a sill upon which the joint member is loosely mounted.
11. In car construction, a side post, wall 45 sheathing adjacent to said post, flooring, the edge of which occupies a position adjacent to the inner face of the wall sheathing, and a joint member interposed between the flooring and sheathing and being rigidly 50 fixed thereto and to the side post.
12. In car construction, a side sill, flooring, wall sheathing, the inner face of which
- sheathing adjacent to the end of the flooring is rabbeted, a joint member resting loosely upon the side sill and interposed between the flooring and wall sheathing, a portion 65 of which joint member occupies the rabbet in said sheathing and attaching means seated in said wall sheathing and that portion of the joint member which occupies the rabbet 70 therein.
13. In car construction, a side sill, flooring, wall sheathing, a joint member resting loosely upon said side sill, a portion of which joint member occupies a recess formed 75 between the end of the flooring and the inner face of the sheathing and attaching means seated in a portion of said joint member and said wall sheathing.
14. In car construction, a side sill, wall 80 sheathing, flooring, the edge of which terminates in the same plane with the inner face of the wall sheathing, a joint member bearing loosely upon the sill and fixed to the flooring and having a portion interposed between the end of said flooring and the adjacent face of said sheathing and attaching means seated in said wall sheathing and the adjacent portion of said joint member.
15. In car construction, floor, wall sheathing, the inner face of which sheathing at 85 the end of the flooring is recessed, and a joint member rigidly fixed to the flooring and having a portion positioned in the recess in the sheathing and rigidly fixed to the 90 latter.
16. In car construction the combination with a side sill, floor and wall sheathing, of a joint member comprising an angle having its horizontally disposed leg resting 100 upon the sill and positioned beneath the edge of the flooring and its vertical leg positioned between the end of the floor and the lower portion of the sheathing, and fastening means seated in the horizontal leg of said 105 joint member and said flooring.
17. In car construction the combination with a side sill, flooring and wall sheathing, of a joint member comprising an angle having its horizontally disposed leg resting 110 upon the sill and positioned beneath the edge of the flooring and its vertical leg positioned between the end of the flooring and the lower portion of the sheathing, and fastening means seated in the vertical 115 leg of said joint member and said wall sheathing.

In testimony whereof I hereunto affix my signature in the presence of two witnesses, this 15th day of May, 1915.

JACOB H. WEISBROD.
